UNITED STATES PATENT OFFICE.

SAMUEL NEAL McCLEAN, OF WASHINGTON, IOWA.

GAS-OPERATED FIREARM.

SPECIFICATION forming part of Letters Patent No. 783,453, dated February 28, 1905.

Application filed March 11, 1899. Serial No. 708,737.

To all whom it may concern:

Be it known that I, SAMUEL NEAL McCLEAN, a citizen of the United States of America, residing at Washington, in the county of Washington and State of Iowa, have invented certain new and useful Improvements in Breech-Loading and Discharge-Actuated Firearms; and I do hereby declare that the following is a full, clear, and exact description of the same.

10 My invention relates to breech-loading and discharge-actuated firearms, and more particularly to automatic and semi-automatic fire-arms.

The object of the invention is to utilize the force of the discharge for operating the arm and to provide certain means for controlling and modifying the force of the discharge, also to cause the force of the discharge to operate on the different parts of the arm in any 15 such manner as the safe, easy, and advantageous action and coaction of the parts may require.

Guns of the above kind as heretofore constructed when discharged by any of the high-pressure powders have been subjected to enormously severe and injurious firing strains, and the action of these strains on the operating parts of the arm as heretofore constructed has been such as to subject the operating parts to a great variety of severe, transverse, torsional, complex, and destructive strains, which strains on the construction and action of the operating parts has tended to render the operation of the arm dangerous, 20 uncertain, and difficult, also to shorten the life and endurance of enormously-expensive arms and to materially and injuriously affect their accuracy of fire.

One object of my invention is to construct 25 a gun in which the strains of firing shall be received in the line of greatest strength, distributed correctly on every part of the arm, limited to the least possible area, and that the plan of the operating parts shall not cut away 30 and destroy the strength and symmetry of the frame.

In quick-firing guns, such as the ordinary machine-gun, as heretofore constructed the manner in which the firing strains have been 35 received and distributed on the operating

parts of the arm has been such as to render the construction of these arms complex and very expensive and to render their operation uncertain, irregular, and liable to breakage, and this has been especially true of such guns 55 when actuated by the direct force of the discharge. One object of my invention is to provide certain means by which the discharge actuating force shall be controlled to exert its power on the operating parts in such manner 60 as will not be injurious to the same and will remedy the above difficulties.

Another object of my invention is to construct a gun in which the plan of the operating parts shall be formed to handle ammunition by the most direct and simple movements 65 and combinations attainable.

I attain some of the results before described by means of certain regulating devices for controlling the application of the force of the 70 discharge to the bolt-action, which means may be formed to give any required power in operating the bolt-action to either increase, prolong, or diminish the same and may be controlled positively at will.

I also attain some of the above results in 75 gas-actuated guns by connecting the bolt-action with a gas-controlling device which utilizes the ball as a valve to govern and prolong and either increase or diminish the power of 80 the gas in operating the bolt.

I also attain some of the foregoing improvements by constructing a gun in which the breech mechanism is combined with gas-controlling means and a gas-catching chamber of 85 such length and diameter that the breech mechanism is thrown to open position while the ball is passing through the chamber.

My invention also consists in a gun having a breech mechanism actuated by the force of 90 the discharge, combined with means which permit the breech mechanism to act freely during its movement to open position, but which retard the action of the same while in the act of returning to firing position; and, 95 finally, the invention consists in certain details of construction and combination of parts, which will hereinafter be more fully described and then pointed out in the claims.

In the accompanying drawings, which are 100

hereby made a part of this specification, Figure 1 is a broken longitudinal central section of the arm with parts in elevation and the operating parts in their rear or loading position. Fig. 2 is a longitudinal sectional view of the magazine, illustrating the action of the cartridge-lifter T and the cartridge-feeding pawl U, together with the driving-rod F and cartridges. Fig. 3 is a top view of the magazine-door S. Fig. 4 is a transverse section of the magazine-door, taken on the line c c of Fig. 3. Fig. 5 is a transverse section of Fig. 6 on the line d d. Fig. 6 is a side view of the magazine-door S. Fig. 7 is a transverse sectional view taken on the line b b of Fig. 1, showing the flanged relation of the handle P with the frame. Fig. 8 is a transverse sectional view of the arm, taken through the rear end of the magazine R and through the rear end of the driving-rod F. Fig. 9 is a transverse section of the weapon on the line a a of Fig. 1, showing the hinged relation of the cartridge-lifter T and cartridge-feeding pawl U with the frame C. Fig. 10 is a side elevation of the cartridge-feeding pawl U. Fig. 11 is a transverse section of Fig. 10 on the line e e. Fig. 12 is a bottom view of Fig. 10. Fig. 13 is a side elevation of the cartridge-lifter. Fig. 14 is a transverse section of Fig. 13 on the line f f. Fig. 15 is a top view of Fig. 13. Fig. 15^a is a section on line 15^a 15^a, Figs. 13 and 15. Fig. 16 is a longitudinal central sectional view of the barrel and receiver with parts in elevation and illustrating the operating parts in the forward or discharged position. Fig. 17 is a bottom plan view. Fig. 18 is a side elevation, and Fig. 19 is a rear end view, of the driving-rod F. Fig. 20 is a rear elevation of the bolt-timing latch D', with its flanged construction shown by transverse sections on the lines k k and l l. Fig. 21 is a rear end view of the breech-bolt D, showing the bolt-timing latch D' and the spring by which the latch is actuated. Fig. 22 is a bottom plan view of the breech-bolt, showing the bolt-timing latch D' and the cam-faces D², by which the bolt is rotated. Fig. 23 is a front end view of the breech-bolt, showing the manner in which the body part of the bolt is cut out to permit the cartridge-magazine to rise up into line with the barrel. Fig. 24 is a longitudinal central section of the breech-bolt, taken on the line j j, of Fig. 23. Fig. 25 is a side elevation and top view of the shell-extractor. Fig. 26 is an enlarged side elevation of the forward part of the frame C, illustrating the relation of the driving-rod F to the piston V, which controls the firing speed of the arm. Fig. 27 is a transverse section of the frame C, showing the piston V and its control-valve in elevation. Fig. 28 is a transverse section of the frame C and the handle P on the line g g, Fig. 16. Fig. 29 is a side elevation of the handle. Fig. 30 is a side elevation of the magazine, showing the feed-latch R'. Fig. 31 is a top view of Fig. 30, showing the feed-latch R' and the manner in which the lugs R² project into the magazine, together with the flange at the rear end of the magazine for guiding and retaining the cartridge-clip. Fig. 32 is a side elevation of the magazine cut-off W, showing its handle part W' and the cam-face W², by which it lifts the cartridge-feeding pawl out of action. Fig. 33 is a section of Fig. 32 on the line m m. Fig. 34 shows in elevation the pawl V, which governs the speed of firing, and its valve V' detached. Fig. 34^a is a section on the line z z, Fig. 34. Fig. 35 is a broken view of the upper side of the handle P, as shown in Figs. 16 8 and 29, illustrating the construction of the handle-latch Q². Fig. 36 is a broken view, partly in section, of the rear end of the barrel and forward end of the receiver, illustrating the bolt-locking shoulders A' of the receiver. Fig. 37 is a detailed plan view of the firing-pin and the screw-collar by which it is retained in the breech-bolt. Fig. 38 is a horizontal section of the barrel and receiver, showing the shoulders A', the retaining-wings 90 of the magazine R on its upper side, and the guides C' of the frame C, on which the breech-bolt rests when it is reciprocated. Fig. 39 is a front end view of the gas-chamber. Fig. 40 is a part section, part side elevation 95 of the gas-chamber, showing the screw-thread by which it is attached to the barrel, also the gas-tube G and the manner in which this tube is attached to the gas-chamber, together with the opening I', through which the tube communicates with the gas-chamber. Fig. 41 is a horizontal section of the magazine, taken on a line with the cam-lugs R² of Fig. 30 and showing the driving-rod F and the cam-lugs F² on the under side of the rod F, which 105 actuate the lugs R² to withdraw the lugs R² in operating the magazine-feed R'. Fig. 42 is a vertical section of the parts shown in Fig. 41. Fig. 43 is a side elevation of the right-hand side of the arm with the right stock-wall broken 110 away. Fig. 44 is a central sectional view of a modification of the gas-chamber. Fig. 45 is a side elevation, partly in section, of a modification of the gas-chamber, in which a portion of the gas-chamber is integrally formed with the 115 barrel. Fig. 46 is a vertical central section of the cartridge-clip. Fig. 47 is a central sectional view of the forward end of the gas-chamber, showing, on an enlarged scale, the gas-plug I' in elevation; and Fig. 48 is a broken longitudinal section of the muzzle end of one form of the barrel. 120

In the accompanying drawings, the receiver is denoted by the reference-letter A, the barrel by the reference-letter B, the frame by the reference-letter C, the breech-bolt by the reference-letter D, the extractor by the reference-letter E, the driving-rod by the reference-letter F, the gas-tube by the reference-letter G, the driving-spring by the reference-letter H, 130

the gas-chamber or gas-catcher by the reference-letter I, the cartridge-ejector by the reference-letter K, the trigger by the reference-letter L, the sear by the reference-letter M, 5 the firing-pin by the reference-letter N, the trigger-lock by the reference-letter O, the handle by the reference-letter P, the handle-latch by the reference-letter Q, the magazine by the reference-letter R, the magazine-door 10 by the reference-letter S, the cartridge-feeding pawl by the reference-letter U, the cartridge-lifter by the reference-letter T, the pawl which governs the speed of firing by the reference-letter V, the magazine cut-off by the reference-letter W, and the cartridge-clip by the reference-letter X.

The receiver may have any form necessary to adapt it to the type of breech-bolt action with which it is intended to be used; but for 20 the purpose of attaining certain manufacturing and military advantages I prefer to form the receiver as a hollow cylinder of sufficient length to entirely house the bolt action in both its front and rear positions and provided on 25 its upper side with an opening through which the cartridges may be inserted or ejected and on its under side with an opening in which the driving-rod may be reciprocated, and through which the magazine-feed of the cartridges 30 may be accomplished. The forward end of the receiver is formed with cavities or recesses located on its opposite sides, and both the front and rear faces of these cavities are cammed or beveled to cause the operation of the bolt- 35 action to close home powerfully against the end of the cartridge in locking and to start the withdrawal of the shell by the unlocking rotating action of the bolt. To prevent the receiver from springing under the strain of 40 firing, these cavities are located immediately to the rear of the barrel and have their front walls beveled to provide additional stiffness of the receiver between the lugs A', forming the rear walls of the cavities, and the end of the 45 barrel. The lugs A' are also beveled across their rear corner to afford additional thickness to resist the thrust of the breech-bolt at its point of greatest strain. The rear end of the receiver is formed with an interrupted 50 thread which is cut out to permit the end of the receiver to be closed by a dust-cap A', which is formed with a corresponding interrupted thread.

The breech-bolt has a general cylindrical 55 shape and is preferably integrally formed from a bar of metal. The bolt-head is formed with locking-lugs D', which are beveled on their forward side to adapt them to the cavity forward of the lugs A' in which they are rotated, and the forward end of the bolt is provided with an extractor-seat D', Figs. 22 and 30, the bottom of which extractor-seat in longitudinal section is formed on an arc of a circle to cause the extractor to swing on the arc when 60 it engages with the cartridge and to positively

retain it in engagement with the cartridge. The body part of the breech-bolt is cut out on its under side in order to permit the breech-bolt to pass over the top of the magazine, which is elevated nearly into line with the bore of 70 the barrel. This part of the breech-bolt is provided on its opposite sides with reverse cam-faces D'', which are engaged by the shoulders F' of the driving-rod (see Figs. 1, 8, 16, and 18) to rotate the block in opening and 75 closing the breech. These cam-faces D'' have a straight part at their forward end to permit the firing action of the drive-rod after the bolt is locked. The rear end of the breech-bolt is provided with a flanged guideway D', 80 Fig. 24, to receive the bolt-latch D' of Figs. 20 and 21. This latch D' is a flanged slide to adapt it to the breech-bolt and is beveled across its upper edge for engagement with the receiver and is V-shaped on its lower edge 85 for engagement with the driving-rod. It is also provided on its rear side with a chamber in which its actuating-spring is seated.

The shell-extractor has a forward hooked extremity for engagement with the flange of the cartridge and has on its under side near its rear end a flange which in longitudinal section is formed on an arc of a circle to adapt it to the extractor-seat in which it is retained. It is also provided with a coiled spring E' to 95 exert a yielding tension thereon.

The frame C is formed to be attached to the under side of the receiver by a lip C', Fig. 2, for engagement with the receiver, and at its forward end it is attached to the receiver by 100 the screw C' of Fig. 1. This frame C is provided in its middle part with an opening to receive the magazine R and at the rear of the magazine is cut out or mortised to permit the insertion of the trigger L, sear M, and cartridge-ejector K. It is provided with a rearwardly-extending guard-strap C'', which is formed with lateral flanges to receive and guide the handle P. In front of the magazine-chamber the frame C is provided with a 110 circular chamber, Figs. 1 and 2, in which is pivotally supported the cartridge-lifter T and the feed-pawl U, which governs the magazine-feed, and in the forward end of the frame C is located another circular chamber in which 115 is located the pawl V, which governs the speed of firing by means of an oil-pressed valve.

The cartridge-magazine R, Figs. 1, 2, 8, 16, 120 30, and 31, is preferably formed of sheet metal, and in a general way it conforms to the shape of the cartridges. The rear end of the magazine is flanged to form a guideway R' for the reception of the cartridge-clip, as shown in Figs. 30 and 31. This guideway R' projects rearward and forms a shoulder R'', Fig. 16, which engages with a shoulder a' on the cartridge-clip to retain it in fixed engagement with the guides R' until the magazine is empty. The forward side of the magazine is open to 130

permit the upward movement of the cartridge-lifter, as shown in Fig. 2.

Attached to the sides of the magazine R, Figs. 30, 31, are the cartridge-feed latches R', which are provided with lugs R², lying in the path of and engaged by the cam-lugs F², Figs. 17 and 18, of the driving-rod, and the upper extremity of these cartridge-feed latches is provided with lugs R³, which are moved into and out of the path of the cartridges. The upper edges of the magazine are inwardly curved to extend into the path of the upward movement of the cartridges and operate as a stop to govern the passage of the cartridges from the magazine into the barrel.

The gun is operated by the driving-rod F, which may be actuated either by hand or by the force of the discharge. The rear portion of the driving-rod is bifurcated, Fig. 17, in order to allow its arms to be reciprocated on the opposite sides of the magazine, while its extreme rear end is provided with a latch-shaped projection F' for engagement with the latch D' to connect the drive-rod and the breech-bolt. The drive-rod is also provided with shoulders F², Fig. 8, which engage with the cam-guides D² of the breech-bolt, Figs. 1, 8, and 19. The lug F', Fig. 19, reciprocates between the wings R⁴ of the cartridge-magazine and is guided in its reciprocating movement by the guides C', formed on the upper part of the frame C, as shown in Fig. 38.

On the driving-rod F is formed a lug F², which is provided with a cam-face (see dotted lines, Fig. 18) on its inner side to engage with and operate the cartridge-feed U. On the under side of the bifurcations of the driving-rod are formed the cam-lugs F², as shown in Figs. 17 and 18. These lugs open or spread the cartridge-feed latches R' by engagement with lugs R², Figs. 30 and 31. The lugs F', as shown in these figures, are formed on the right-hand side of the driving-rod to engage with the speed-firing pawl V, Fig. 26.

The forward end of the driving-rod F is preferably formed of a hollow tube, as shown in Figs. 17 and 18, and at its front end is provided with a piston which may have suitable grooves to contain a lubricating preparation to prevent corroding of the gas-tube G by the action of the gases of discharge.

The gas tube or cylinder may be formed of any suitable material; but I prefer to form it of nickel-steel to reduce the injury due to the corroding action of the gases of discharge. This tube is provided at its rear end with a screw-plug G', against which the driving-spring H bears, as shown in Fig. 16, and the forward end of the tube is threaded to be screwed into the gas-chamber I, as shown in Figs. 40 and 45, and may be screwed into the gas-chamber I' to reduce the opening into the gas-chamber, thus forming an adjustment to control the quantity of the gas admitted to the tube. In Fig. 40 the front end of this

tube G is shown cut out on its upper side to form an opening for the admission of the gas, and its under side operates to close the outer end of the opening I², thus doing away with the necessity for plugging this opening I² on the under side of the gas-chamber.

The gas-chamber I may be either integrally formed with the gun-barrel, as in Fig. 45, or it may be formed to be detachably attached to the gun-barrel, as in Fig. 40. The gas-chamber when formed as a chambered piece to be attached at the end of the barrel consists of a cylinder having a bore which is formed in line with the bore of the barrel and the rear end of which is threaded to allow the chamber to be screwed to the end of the barrel. This gas-chamber has a bore or longitudinal chamber which is sufficiently larger than the ball or projectile to allow a portion of the gas of discharge to escape around the ball, thus reducing and relieving the gas-pressure in the gas-chamber and at the same time utilizing the ball during its passage as a valve in catching and retaining the required gas-pressure to operate the arm. The under side of the gas-chamber in this detachable construction is formed with a projecting arm or bracket which is provided with a chamber or opening communicating with the longitudinal part of the gas-chamber and which is threaded to permit the insertion of the gas-tube G.

The extension of the gas-chamber I', Fig. 40, is a tube having its front end open for the free passage of the projectile and is provided with a screw-thread on its inner side to engage with a companion thread on the gas-chamber. This extension I' is knurled to afford a convenient means of adjusting it.

In the modification of the gas-chamber which is shown in Fig. 45 the longitudinal part of the gas-chamber is formed integrally with the barrel and is of a diameter sufficiently larger than the barrel to permit the escape of the gas around the ball and has a length which may be varied to suit any length of time during which the gas-pressure is required, and the diameter of its bore may be decreased or diminished or may be of any required size to secure in the gas-tube G the desired gas-pressure necessary to operate the breech mechanism. This preferred form of construction of the gas-chamber controls the quantity of gas which shall be forced into the gas-chamber and the power which it shall exert in the same and the length of time the desired gas-pressure shall be retained in the chamber. In this form of the gas-chamber the part I' is formed as a detachable band which may be slipped onto the end of the barrel until it arrives over the opening I² on the under side of the barrel, and at which point it is fixedly retained by the pin I¹. This band is provided with a threaded chamber for the reception of the gas-tube G and has an opening which communi-

cates with the opening I^1 . This band I^1 may also be formed to act as a band or holder to retain the forward end of the fore-stock, as is usual in an arm provided with a musket style of stock. The gas-chamber I' is also provided at its forward end with a screw-plug I^1 , having a flaring outer end to cause the plug when screwed into the gas-chamber to diminish the size of the bore of the gas-chamber, as shown in Fig. 47, thus increasing the pressure of the gas within the chamber. The band I^1 is knurled on its outer side and threaded on its inner side to engage with a companion thread on the chamber I for the purpose of either partially or entirely closing the opening I^1 into the gas-chamber.

The driving-spring H is formed to be retained in the tube G and to exert a yielding tension on the driving-rod and is preferably lubricated with a preparation formed of oil and black-lead or plumbago to prevent corrodung and rusting.

The rotary piston V , which governs the speed of firing, (see Figs. 16, 26, 27, and 34,) has a body part V^1 and the projecting arm V^2 and is supported in a cylindrical chamber formed in the forward end of the frame C by the pivots V^3 , on which it turns, and its body part is provided with a valve-seat V^4 , in which is located the valve V' . The chamber V^5 , in which this piston is located, is closed by a circular disk V^6 , which is screwed into it, as shown in Fig. 27, and on its upper side the chamber is provided with a partition V^7 . The chamber is filled with oil, and the device controls the speed of firing, as hereinafter set forth.

The cartridge-ejector K is pivotally supported in the frame C , and its forward end is located in the path of the terminal movement of the breech-bolt and is notched to form an engagement with the cartridge. It is engaged by the spring K^1 and has a cam-lug K^2 projecting laterally from its rearward end into the path of a cam F^1 on the heel of the driving-rod F . The sear M is also pivotally supported in the frame C and has a rearward extremity, which rises into the path of the driving-rod F , and a forward extremity, which is provided with notches M^1 and M^2 to engage with the trigger and to govern both the single-firing and speed-firing action of the weapon.

The trigger L is pivotally supported in the frame and has the usual outward-projecting finger part for actuating it, and at its upper end it may be provided with a nose L' , hinged thereto, which acts as a toggle-joint to augment the lifting or disengaging power of the trigger.

In the modification of the trigger shown in Fig. 48 the nose L' is integrally formed with the upper end of the trigger and has a direct engagement with the sear by means of a cam-face, and the modified form of the sear M^3

shown in the same figure is attached at the side of the receiver to govern the forward-firing action of the driving-rod, and in such construction the lugs F^1 and F^2 , Fig. 48, of the driving-rod F correspond to the sear-notches M^1 and M^2 , as shown in Fig. 1.

The trigger cut-off O , Figs. 1, 16, 29, and 43, is a slide which is mounted in the handle P and is movable into and out of the path of the trigger. It is provided on its under side with a lug to engage with the notches P^1 , P^2 , and P^3 of the handle P . (See Fig. 1.) The auxiliary sear-lug O' engages with the auxiliary sear M^3 to control the single-loading and single-firing action of this sear, Fig. 48.

The handle-latch Q , Figs. 16, 28, and 38, is a spring-latch formed to engage and retain the handle locked in its forward position and to be disengaged from the handle by a pressure of the thumb or finger. In Fig. 28 it is shown as a spring-stud carried in the frame C , and in Fig. 16 a modification of the handle-latch is shown at Q^1 , where it is shown as a thumb-piece which is pivotally supported in the handle P and is spring-pressed to engage with the frame C and pressed by the finger to release the handle. The handle is connected with the driving-rod F by the connecting-rod P^4 , Fig. 1, whose forward end enters the tube or forward part of the driving-rod F and is retained in the driving-rod by means of a screw F^3 , (shown in Figs. 17 and 18,) so that the rod P^4 can telescope with the tubular part of the driving-rod, but cannot be entirely withdrawn therefrom.

The cartridge-lifter T is pivotally supported in the frame C on the pivot C^6 . It conforms to the shape of the cartridge and has its pivotal end chambered to provide space for its actuating-spring T^1 , which is coiled about the pivot C^6 . It is provided with a lug T^2 for engagement with a shoulder on the magazine-door and with a ratchet T^3 , Fig. 13, to engage with the feeding-pawl U' , by which it is operated.

The cartridge-feeding pawl-lever U is pivotally supported in the frame C by the pivot C^6 and has a disk-shaped body, which is chambered to provide a space or opening for its actuating coiled spring U^1 . It is also provided with a pawl U' , which engages with the ratchet T^3 . On its rearwardly-projecting arm is located a cam-faced lug U^2 , which lies in the path of and is engaged by the driving-rod. The pivot-bearing of the pawl-lever is elongated toward its lower side to permit the pawl-lever to be shifted by the cartridge cut-off, and thus disengaged from the ratchet T^3 .

The magazine-door S is supported in the frame C on the pivot C^6 and has a hub part which is cut out to afford space for its actuating coiled spring, Fig. 6, a cam-face S^1 for engagement with the feeding pawl-lever U , and a shoulder S^2 to engage with the cartridge-lifter T . The rearwardly-projecting arm of

the magazine-door is preferably flanged to form a covering for the magazine.

The magazine cut-off W , Figs. 32 and 33, is disk-shaped and is provided with a thumb-piece W^1 and a cam-face W^2 and is pivotally supported on the outer side of the magazine by the pivot C . (See Fig. 16.)

The cartridge-clip x , Fig. 46, has a flanged guideway x^1 for engaging with the flange or groove of the cartridges, and its respective opposite ends are formed with integral spring-latches x^2 to retain the cartridges in fixed relation with the clip and to release the same when actuated by the magazine-feed. The middle part of the cartridge-clip is provided with an integrally-formed projection or lug x^3 to engage with the shoulder R^3 of the guideway R^1 of the magazine and retain the cartridge-clip in fixed relation with the magazine during the operation of the cartridge-feeding pawl. The cartridge-clip x is also formed to be retained in position by the magazine-door when closed and to drop out when the magazine-door is open or to be turned out by engagement with the cartridge-lifter.

The operation of the gun is as follows: Supposing the operating parts to be in the withdrawn or loading position and the breech-bolt resting in the rear part of the receiver, the discharge of the arm is effected by a pull of the finger on the trigger L . This causes the sear M to be disengaged from the driving-rod F and permits the spring H , through the driving-rod, to advance the breech-bolt until it has pushed the topmost cartridge from the magazine into the cartridge-chamber of the barrel, the connection of the driving-rod and breech-bolt being effected by the engagement of the lug F' with the spring-pressed latch D' . This latch is retained in engagement with the driving-rod by the pressure of its spring and prevented from disengaging from the driving-rod by the fact that the upper end of the latch D' is formed to bear against the upper inner side of the receiver-wall, which prevents it from rising and unlatching from the driving-rod until the bolt has been advanced to its forward position and the upper end of the latch D' is brought into the cut-out or segmental groove A^1 in the receiver, at which time the force of the forward movement of the driving-rod causes the latch D' to be lifted by the cam action of the lug F' on the V-shaped lower end of the latch, thus permitting the driving-rod to be disconnected from the latch and to cause the shoulders I^1 on the driving-rod, Figs. 8, 16, and 19, to traverse the cam-faces D^2 on the under side of the breech-bolt and accomplish the rotating locking action of the bolt. The straight part of these cam-guides D^2 permits the driving-rod to have a limited forward movement after the locking action of the bolt is complete, and this terminal movement of the driving-rod effects the discharge of the weapon by bringing the driving-

rod into contact with the rear end of the firing-pin. The shell-extractor E , Figs. 16, 22, 24, and 25, is brought into latched engagement with the cartridge by this advance movement of the breech-bolt, and its operation is as follows: The arched construction of the extractor-seat D^3 and the corresponding curve of that part of the extractor which engages with the extractor-seat are such that they permit the extractor to slip or turn on the arc of the extractor-seat sufficient to allow its forward end to be raised over the flange of the cartridge by the beveled shape of the extractor, and the pressure of the spring E' causes the extractor to drop into locked engagement with the cartridge as soon as its forward end has passed beyond the cartridge-flange. This arched construction of the extractor-seat permits the extractor to be firmly retained in the extractor-seat and at the same time swing freely for a sufficient distance to engage the cartridge. It also causes the extractor to close down and maintain a fixed locked engagement with the cartridge as soon as the extracting pull is begun.

Upon the discharge of the weapon the gas-chamber utilizes the ball as a valve to control the power of the gas in actuating the breech mechanism. This result is attained as follows: When the ball, driven by the force of the gas, has passed through the barrel and emerges into the gas-chamber I' , the funneled or tapered shaped of the rear end of the chamber I' permits the gas to escape around the ball, thus permitting the gas to escape gradually until a satisfactory reduction of the gas-pressure is effected, this being determined partly by the size of the chamber I' . During the passage of the ball into and through the chamber I' it partially plugs up or closes this chamber and in so doing operates as a valve which causes the gas to be partially checked, and a portion thereof passes through the opening I^2 into the gas-tube G , driving the piston I^3 back, and thus causing the driving-rod F to unlock and withdraw the breech-bolt. It is thus apparent that the gas-chamber controls the force and action of the gas-current and the operating parts of the arm by permitting the gas to escape around the projectile before the force of the gas-current is brought to bear on the action, thus using the ball as a valve to secure any desired or required reduction in the pressure of the gas-current before the force of the gas-current is thrown on to the action. It is also apparent that the gas-chamber maintains the operating pressure of the gas-current on the operating parts by causing the projectile to act as a valve during the entire time that the projectile is passing through the gas-chamber.

The quantity of gas required to operate the action may be controlled in any one of several different ways. In the first place, in order to reduce the gas-pressure and cause it to exert

a sufficiently gentle force in the operation of the arm, the gas-chamber I' may be formed to have any required diameter, thus allowing any desired amount of the gas to escape around the ball and reducing the gas-pressure in this way to any desired degree. The proper pressure will depend upon the relation of the gas-chamber to the bore of the barrel and to the size of the projectile and to the pressure of the gas in discharging the projectile. It is apparent that the bore of the gas-chamber I' may be increased or diminished by means of a screw adjustment or any other mechanical device suitable for the purpose, thus allowing the quantity of the gas which is caught and deflected by the gas-chamber to be controlled at will, for which purpose I have shown a screw-adjusting nozzle I', Figs. 45 and 47, and it is also apparent that a slot and adjustable baffle, Fig. 45, may be utilized to allow a portion of the gas to escape from the chamber I' for the same purpose, and it is further apparent that the length of the gas-chamber can be lengthened or shortened, as shown in the screw-adjustable tube I', Fig. 40, thus prolonging or shortening the action of the gas-current, all of these several means affording a means of increasing the operating power to adapt it to a dirty gun or to crooked or deformed ammunition.

In the construction of the gas-chamber shown in Fig. 48 the lip or projection I' is actuated by the gas-current to prevent the tendency of the point of the arm to be thrown up by the force of the recoil, and it is also apparent that the forward pressure of the gas-current in the gas-chamber reduces the recoil to a minimum.

The breech-bolt is both reciprocated and locked by the direct action of the driving-rod F, driven by the gases of discharge, acting against the piston F', which piston may be lubricated by any suitable oil mixed with plum-bago or black-lead. This should be mixed to a proper consistency and placed in the grooves of the piston and upon the walls of the gas-tube G, and when so placed it will effectually prevent rusting and the corroding action of the gases of explosion, as well as the formation of scales or crust on the inside of the gas-tube.

The unlocking and withdrawal of the breech-bolt is effected by the driving-rod in a manner which is the reverse of that described in its forward and locking movement. During the initial part of the driving-rod's rearward movement the shoulders F' traverse the straight part of the cams D' on the block, and thus permit the drive-rod to start freely on its unlocking movement of the bolt, so that when it commences to traverse the cam-faces D' it has considerable momentum of movement, thus overcoming any tendency of the breech-block to stick. The drive-rod in both its forward and rearward movement is fixedly guided by the opening A' on the under side of the receiver in which it is moved and by its engagement with the frame C. The movement of the drive-rod causes the shoulders F' as they push past the cam-faces D' to roll the bolt into its unlocked position, and when the lug F' of the drive-rod comes into engagement with the latch D' in the end of the bolt the cam or beveled face on the rear side of the lug F' causes the cam-face on the under side of the latch D' to be lifted up into the cut-out part or groove A' of the receiver, thus preventing the breech-bolt from starting back until the lug F' has brought its V-shaped notch into engagement with the V-shaped end 80 of the slide D', permitting the slide D' to drop down out of the groove A' and allowing the breech-bolt to be withdrawn in a straight line after the unlocking of the bolt action is complete and preventing this action until the bolt is fully unlocked.

The lug F' on the driving-rod will on account of its length come into contact with the under edge of the latch D' slightly before the locking-lugs of the bolt have been entirely freed from the locking-lugs of the receiver, whereby the drive-rod lifts the latch D' before the rolling movement of the bolt is fully completed, thus causing the drive-rod to latch positively with the bolt at a fixed point and preventing any possibility of clogging. It is thus apparent that the driving-rod governs positively both the reciprocating and locking action of the breech-bolt and compels it to both lock and unlock at a fixed point.

The cartridges are ejected by the terminal rearward movement of the breech-bolt acting upon the cartridge-ejector K, which is lifted into engagement with the rear end of the cartridge by the action of the cam-face F' against its companion cam-face K' on the rear end of the ejector, which causes the ejector to rise into the path of the rearward movement of the cartridge-shell and throw it out of the receiver slightly before the bolt has reached its rearmost position.

The cartridges are fed up into the path of the breech-bolt by the action of the cartridge-lifter T, which is actuated by any suitable spring, as the coiled spring T', the cartridges being guided in the magazine either by a cartridge-clip, which is retained in the magazine until empty of its cartridges, or the cartridges may be placed loosely in the magazine either from a magazine-filler or by hand, and for the purpose of assisting and governing the magazine-feed the operation of the cartridge-latch is as follows: The function of this latch is to retain the cartridges against the pressure of the cartridge-lifter until after the breech-bolt has been withdrawn beyond the top of the magazine, at which time the cam action of the lugs F' on the lugs R' of

the magazine-latch causes the projections R^2 to be withdrawn from the path of the cartridges and allows them to feed up freely into the path of the bolt. When the magazine-clip is allowed to remain in the magazine, the feeding action of the cartridge-lifter T is rendered more powerful by the operation of the cartridge-feeding pawl U . This pawl U when the magazine is full of cartridges 10 engages with the first notch of the ratchet T^2 by means of the pawl U' , and the cam-shaped end U^3 of the pawl-lever is retained in the path of the rearward movement of the cam-lug F^2 of the driving-rod. The cam-face of 15 this lug F^2 engages with the lug U^3 , and the terminal part of the rearward movement of the driving-rod causes the pawl U to lift powerfully on the cartridge-lifter and to force the cartridges up into line with the bore of 20 the barrel by the direct and powerful combination with the driving-rod and to retain the cartridges in this position until the forward movement of the driving-rod frees the lug U^3 from the lug F^2 of the driving-rod and permits 25 the force of the coiled spring U^5 , Figs. 1 and 10, to swing the pawl U' into engagement with the second notch of the ratchet T^2 . This gives a positive and powerful feeding of 30 the cartridges and one which is sufficient to force the cartridges out of the clip.

The operation of resfilling the magazine with cartridges is as follows: The magazine-door S is turned on the pivot C^6 by hand, and when it has moved a sufficient distance it brings the 35 lug S' into contact with its companion lug T' of the cartridge-lifter. (See Fig. 1.) The further movement of the magazine-door causes the cartridge-lifter T to be swung down out of the magazine for the reception of its complement of cartridges. The magazine may be 40 filled either singly by hand or from a cartridge-holder containing the required number to fill the magazine, and when the cartridge-holder is used it is connected with the magazine, and 45 the cartridges push from it into the magazine when the holder is withdrawn. I prefer, however, in operating the magazine to use a cartridge-clip similar to that shown in Fig. 46, which consists of a flanged guideway having 50 an integrally-formed springcartridge-retainer at its respective opposite ends and provided with an integrally-formed lug x' to retain it in the magazine.

The cartridge-clip when inserted in the 55 magazine is pushed up through the guide R^4 until the lug x' engages with the shoulders R^5 , Fig. 46, at which time the magazine-door and cartridge-lifter are closed.

The operation of the magazine cut-off is as 60 follows: The thumb-piece W' of the cut-off is grasped by the thumb or finger, and the cut-off is turned until the cam W^2 engages the pin U^1 projecting from the side of the pawl, thereby lifting the latch-shaped lug U' out of engagement with the ratchet T , the elongated

pivot-opening in the pawl-lever permitting this, and thereby preventing the feed from operating on the cartridge-lifter.

The firing speed of the arm is controlled by a rotary piston having a valve which permits a free passage of an oil-current in one direction and compels the oil to flow slowly back in the opposite direction. The piston V is formed to be rotated in a chamber C^6 , formed in the forward end of the magazine. This 70 chamber is provided with a partition V^6 , Fig. 27, which extends radially from the center of the chamber to its circumference. The piston V has a projecting arm V^2 and fits closely in the chamber C^6 and is pivotally supported in 75 the same to afford a limited rotating movement on the pin V^8 . The chamber is closed by the disk or plate V^4 and is filled with any suitable oil. The valve V^1 is slightly movable in the valve-seat V^2 and permits the oil to flow 80 freely in one direction and slowly in the other. The arm V^2 , as shown in Figs. 1, 16, and 26, projects into the path of the lugs F^1 on the driving-rod F , and when the driving-rod approaches the terminal part of its rearward 85 movement the forward and longer lug F^1 engages with the arm V^2 and rotates the piston in the chamber C^6 , the valve opening and allowing the oil to pass freely from its front to its rear side until the arm V^2 has been swung 90 over to the position illustrated in Fig. 1. The reverse movement of the driving-rod causes the arm V^2 to engage with the short or rear lug F^1 and to swing the piston in an opposite direction, the pressure of the oil-current causing the valve to close so that the arm V^2 retards the forward movement of the driving-rod F until the oil has flowed slowly back to the opposite side of the valve through the 95 small openings V^3 in the valve-seat, thus causing the movement of the drive-rod to be retarded by the flow of the oil-current.

Having now particularly described and ascertained the nature of my said invention and in what manner same is to be performed, I declare that what I claim is—

1. In a gun, the combination of a barrel and a receiver with a reciprocating and rotating breech-block having reversely-inclined cams on its opposite sides, and a slide actuated by the gases of discharge and provided with shoulders on its opposite sides in operative engagement with said cams on the block.

2. In a gun, the combination of a reciprocating breech-bolt, a driving-rod connected with the breech-bolt and movable in a gas-tube, and a spring engaging the driving-rod, with a gas-chamber at or near the muzzle of the barrel in communication with said gas-tube, said chamber slightly exceeding in diameter the bore of the gun-barrel, and being of such length that the breech-block reaches open position as the ball leaves the chamber.

3. In a firearm, a gas-chamber which utilizes the ball as a valve to catch, or control, the

- escaping gases of the discharge, in combination with a gas-tube connected with the gas-chamber, the driving-rod and piston movable in the gas-tube, a breech-bolt connected with the driving-rod, a cam-latch carried by the breech-bolt and controlling the engagement of the driving-rod with the breech-bolt and a driving-spring in combination with the driving-rod: 5
10. 4. In a firearm, a gas-chamber which utilizes the bull as a valve to catch and control the escaping gas, a gas-tube connected with the chamber, a driving-rod movable in the gas-tube, a reciprocating breech-bolt, a cam-latch carried by the breech-bolt and governing the co-operation of the driving-rod with the breech-bolt, and a receiver formed with a cam-shoulder for engaging with the said cam-latch to govern the bolt action. 15
15. 5. In a firearm, a gas-catching chamber, a gas-tube communicating with the chamber, a driving-rod movable in the gas-tube and having a piston-head formed with grooves, a lubricating preparation carried in the said grooves of the piston-head, a spring resisting the movement of the driving-rod, and a reciprocating breech-bolt connected with the driving-rod. 20
6. In a firearm, a reciprocating breech-bolt having an extractor-seat which is formed approximately on an arc of a circle, a shell-extractor having a flange, or seat, which is formed on a companion arc, and a spring carried by the extractor to afford a limited, latching movement of the extractor, and to lock the extractor during the process of extracting the shell. 25
7. In a firearm, a driving-rod, a cam-face on the rearward end of the driving-rod, a spring resisting the movement of the driving-rod, a reciprocating breech-bolt connected with the driving-rod, a shell-extractor carried by the breech-bolt, and a shell-ejector engaging with the cam-face on the driving-rod to eject the shell by the terminal movement of the bolt. 30
8. In a firearm, the combination of a driving-rod, the spring resisting the rearward movement of the driving-rod, a breech-bolt connected with the driving-rod, a shell-extractor carried by the breech-bolt, an ejector engaged by the driving-rod, a sear engaging with the driving-rod, and a trigger engaging with the sear. 35
9. In a firearm, the combination of a trigger, having a full swing for single firing and a partial swing for automatic firing, an adjustable trigger-stop movable into and out of the path of the trigger, and retaining means for said stop, securing the latter in or out of the path of the trigger at the will of the gunner, whereby the same may be set for single or automatic firing as desired. 40
10. In a firearm, the combination of a trigger having a full swing for single firing and a partial swing for automatic firing, an adjustable trigger-stop, and means engaging and retaining said stop against the trigger in the normal position of the latter, or out of the path of the trigger or in the path of the swing of the same according to the adjustment thereof. 45
11. In a firearm, the combination of a driving-rod, a breech-bolt connected with the driving-rod, the spring resisting the movement of the driving-rod, a cartridge-magazine projecting into the path of the breech-bolt, a cartridge-lifter movable in the magazine, a pawl engaging with the cartridge-lifter and having a cam-face located in the path of the rearward movement of the driving-rod and engaging with a companion cam-face on the driving-rod to transfer cartridges from the magazine to the barrel. 50
12. In a firearm, the combination of a driving-rod, a spring resisting the movement of the driving-rod, a breech-bolt connected with the driving-rod, a cartridge-magazine projecting into the path of the breech-bolt, a cartridge-lifter movable in the magazine and having a ratchet-and-pawl connection with the driving-rod to transfer cartridges from the magazine to the barrel. 55
13. In a firearm, the combination of a driving-rod, a spring resisting the movement thereof, a breech-bolt connected thereto, a cartridge-magazine projecting into the path of said bolt, a cartridge-lifter movable in the magazine having a ratchet thereon, a pawl operating in conjunction with said ratchet, and having a cam-lug thereon and projecting into the path of an actuating-lug on the driving-rod, whereby the lifter is actuated to raise cartridges into the path of the bolt. 60
14. In a gun, the combination of a driving-rod actuated by the gases of discharge in one direction, a spring actuating the rod in the other direction, a breech-bolt operated by said rod, and yielding means engaging said rod in opposition of said spring. 65
15. In a gun, a driving-rod, a spring resisting the movement thereof in one direction, a breech-bolt connected thereto, a pawl engaged and actuated by the driving-rod, when moving in either direction, a resisting medium in which said pawl moves and a valve in said pawl opening freely in one direction only and a restricted passage through said pawl when the valve is closed whereby the firing speed of the gun is governed. 70
16. In an automatic gun, the combination of breech mechanism, a gas-actuated means operating said mechanism and a gas-chamber controlling the action of the gases of explosion on said means with the devices for adjusting the length of said chamber. 75
17. In an automatic gun, the combination of breech mechanism, gas-actuated devices operating said mechanism; a gas-chamber controlling the action of the gases of explosion 80

on said devices, and constituting an enlargement of the bore of the barrel, and means adjusting the diameter of said chamber at its outlet.

§ 18. In a gun, a gas-chamber formed at or near the end of the barrel, a slot or opening extending through the walls of said chamber

to the atmosphere, an adjustable means governing the size of said slot or opening.
